UNITED STATES PATENT OFFICE.

PARMER R. CROSS, OF LOWELL, INDIANA.

CIDER-PRESS.

SPECIFICATION forming part of Letters Patent No. 315,010, dated April 7, 1885.

Application filed November 25, 1884. (No model.)

To all whom it may concern:

Be it known that I, PARMER R. CROSS, of Lowell, in the county of Lake and State of Indiana, have invented certain new and useful Improvements in Cider-Presses; and I do hereby declare that the following is a full, clear, and exact description of the invention, which will enable others skilled in the art to which it appertains to make and use the same, reference being had to the accompanying drawings, which form a part of this specification, and in which—

Figure 1 is a side view of my improved cider-press. Fig. 2 is a vertical sectional view of the same. Fig. 3 is a horizontal transverse sectional view taken on the line $\alpha\alpha$ in Fig. 1, and Fig. 4 is a top view showing the press-box open for the removal of the pomace.

The same letters refer to the same parts in all the figures.

20 This invention relates to presses for manufacturing cider, and for pressing fruit, cheese, and the like; and it has for its object to provide a combined pressing and straining box which shall possess superior advantages in 25 point of simplicity, durability, and general efficiency.

With these ends in view the invention consists in the improved construction, arrangement, and combination of parts, which will be 30 hereinafter fully described, and particularly pointed out in the claims.

In the drawings hereto annexed, A designates the body of my improved press, which consists of a cylindrical tub or vessel constructed of thick narrow staves B B, which are tapering in cross-section, as shown. The staves are set short distances apart, and are connected at the top and bottom, and, if desired, at suitable intervals, by spacing-blocks C C.

40 The tub or vessel A is constructed in two vertical sections, D and E, which are connected at their rear edges by hinge-joints F, formed by the metallic bands G, which are hinged upon the vertical rod H. The front edges of the sections D and E are connected by hasps I I, the ends of which are provided with slots J, fitting over staples K, and secured by a rod, L, passing vertically through the said staples.

45 The inner sides of the sections D and E of the tub or vessel are lined with perforated sheet metal or wire netting M, forming a strain-

er for the juice expressed by the follower, to be hereinafter described. The said straining material is secured on the inner side by means of vertical strips N N to the staves B, composing 55 the tub or vessel. By this construction great additional strength is gained without detracting from the straining qualities of the device.

O is a follower constructed of heavy planking, and adapted to be operated in any suitable manner by an ordinary screw-press or other suitable means.

The operation of this invention and its advantages will be readily understood from the foregoing description taken in connection with 65 the drawings hereto annexed. The material to be pressed having been placed in the tub or vessel, the follower is inserted and pressure applied, thus expressing and straining the liquid. When the operation of pressing has been completed, the vessel or tub may be opened and 70 the pomace or solid parts or residue thus be readily removed.

The construction is simple and inexpensive, and the device is effective in use and easily 75 operated.

It is obvious that this invention is susceptible to a variety of changes with regard to the construction of minor details, and I would therefore have it understood that I do not limit 80 myself to the precise construction herein described, but reserve to myself the right to all such modifications as may be resorted to without departing from the spirit of my invention.

Having thus described my invention, I claim 85 and desire to secure by Letters Patent of the United States—

1. In a fruit or other press, a tub or press-box constructed of suitably-connected staves, with an interior straining-lining of perforated 90 metal or wire netting, substantially as and for the purpose herein set forth.

2. In a fruit or other press, a tub or press-box constructed of suitably-connected staves with intermediate spaces, and having a metallic straining-lining, said box or tub being constructed in two sections hinged together, substantially as and for the purpose herein set forth. 95

3. In a fruit or other press, a tub or press-box constructed of suitably-spaced staves in two sections, connected by the hinged bands 100

provided with staples and hinged hasps, and a vertical connecting-rod, substantially as and for the purpose herein shown and specified.

4. The combination, with the press-box constructed of suitably-spaced staves with a metallic straining-lining, of the holding-strips secured vertically interiorly to the staves over the lining, substantially as and for the purpose herein shown and specified.
- 10 5. In a fruit or other press, the press-box constructed of suitably-spaced staves in several sections, suitably hinged and connected by

means of the bands, which also serve to connect the staves, in combination with the metallic straining-lining, the interior re-enforcing strips, and the follower, substantially as and for the purpose herein shown and specified. 15

In testimony that I claim the foregoing as my own I have hereunto affixed my signature in presence of two witnesses.

PARMER R. CROSS.
